J. G. C. Mantle
By his attorney
Wm. H. Reid.

UNITED STATES PATENT OFFICE.

JOSEPH G. C. MANTLE, OF LEONIA, NEW JERSEY.

AUTOMOBILE HOOD FASTENER.

Application filed September 3, 1927. Serial No. 217,345.

The object of this invention is to provide a hood fastener which operates in an improved manner, and which is also simple in construction and of neat appearance.

5 The hood fastener mainly consists of a flap-bracket which is secured to the flap of the hood, a base-bracket which is secured to the base-extension of the hood, a swing-member pivoted to the base-bracket, a pull-member 10 slidably mounted on the swing-member and spring-actuated downwardly in the direction of the base-bracket, and means by which the pull-member imparts to the flap-bracket a constant pressure in slantwise direction, 15 downwardly and inclined inwardly in respect to the hood.

In the attached drawing;

Fig. 1 is an elevation of the hood fastener when in fastened position.

20 Fig. 2 is a side elevation of the same.

Fig. 3 is a sectional side elevation showing the hood fastener in unfastened position.

Fig. 4 is a sectional plan through 4—4 of Fig. 2.

25 Fig. 5 is a sectional plan through 5—5 of Fig. 2.

Referring to the drawing, 1 is a portion of the flap of the hood. 2 is a portion of the base extension of the hood. 3 is the flap-bracket.

30 4 is the base-bracket. 5 is the swing-member pivoted on the pin 6, between the two washers 7, to the base-bracket. 8 is a collar secured to the swing-member. 9 is a member slidably mounted on the swing-member. 10 is the pull-member and is slidably on the collar 8.

11 is a member secured to the upper end of the pull-member. The member 9 is secured to the lower end of the pull-member and as the members 9 and 11 are each secured to the pull-

40 member and thus partake of its movements, they may be regarded as portions of the pull-member, as likewise the collar 8 a portion of the swing-member, and thus the pull-member is slidably mounted on the swing-member.

45 12 is a helical spring which cooperates with the swing-member 5 by means of its collar 8 to press the pull-member downwardly towards the base-bracket. The portion 11 of the pull-member is provided with prongs 13 by

50 which the operator manipulates the pull member to fasten and unfasten the hood. The portion 11 of the pull member is provided with arms 14 with which the pull member cooperates with the flap-bracket to fasten the hood. The flap-bracket is provided with a pair of arms which extend embracingly, when

the fastener is in fastened position, one on each side of the pull-member, and terminate in portions 15 to which the arms 14 of the spring actuated pull-member imparts a pressure in 60 slantwise direction, downwardly and inclined inwardly in respect to the hood. 16 is an extension of the base-bracket which serves as a support to hold the pull-member when unfastened to the flap-bracket in the most convenient position for manipulating.

It should be noted (see Fig. 2) that the line of pressure, indicated by the arrow and numeral 17, imparted by the spring by means of the pull-member to the flap-bracket, or, which 70 is the same thing, the line of tension from the contact of the pull member with the flap-bracket to the base-bracket, leans farther away from the flap of the hood, than does the line of pressure, indicated by the arrow and numeral 18, of the spring pressing the pull-member towards the base-bracket.

75 It should be understood that in order to efficiently fasten the flap of the hood of an automobile, the direction of the pressure applied to the flap should be inwards as well as downwards; otherwise a disagreeable rattling noise will occur when the automobile is in rapid motion. The proportion of the inward to the downward pressure required varies in accordance to the shape of the hood but is constant for that particular form of hood. A yielding pressure applied in the correct slantwise direction will give the required proportionate inward and downward 80 pressures. Hitherto, in most instances, this yielding pressure could not be applied in the correct slantwise direction with a fastener consisting merely of a flap-bracket, a base-bracket, a swing-member pivoted to the base-bracket and a spring-actuated pull-member carried on the swing-member; and to remedy this, in many hood fasteners, added parts such as cams and links co-operate with the pull-member. But the fastener here illustrated and described, applies the pressure in the correct slantwise direction and also does not require the added parts in order to be 85 generally applicable.

90 95 100 105 What I claim is:

1. In a hood fastener of the type which fastens the flap by imparting pressure on it in slantwise direction both downwards and inwards in respect to the hood, a flap-bracket secured to the flap, a base-bracket secured to the base extension of the hood, a swing member pivoted on a pivot in the base bracket in 110

a manner permitting a swing-like movement to and from the flap, a pull-member slidably mounted on the swing-member and adapted to fasten the flap by exerting a pressure on the flap-bracket in the line of direction towards the pivot of the base-bracket, a spring carried by the swing-member and pressing the pull-member downwardly in the line of direction towards the pivot of the base-bracket, and means by which the line of direction of the pressure exerted by the spring on the pull-member towards the said pivot.

2. In a hood fastener of the type which fastens the flap by imparting pressure on it in a slantwise direction both downwards and inwards in respect to the hood, a flap bracket secured to the flap, a base-bracket secured to the base extension of the hood, a swing member pivoted on a pivot in the base-bracket in a manner permitting a swing-like movement to and from the flap, a pull-member slidably mounted on the swing-member, a spring carried by the swing-member and pressing the swing-member downwardly in the line of direction towards the pivot of the brace-bracket, the said flap-bracket having a pair of arms extending one on each side of the pull-member, the said pull-member having a pair of arms extending crosswise and adapted

to fasten the flap by exerting pressure on the ends of the arms of the flap-bracket in the line of direction towards the pivot of the base bracket, and means by which the line of direction of the pressure exerted by the arms of the pull member on the arms of the flap-bracket towards the said pivot, leans outwardly in respect to the flap of the line of direction of the pressure exerted by the spring on the pull-member towards the said pivot.

3. In a hood fastener of the type which fastens the flap by imparting pressure on it in slantwise direction both downwards and inwards in respect to the hood, a flap-bracket secured to the flap, a base-bracket secured to the base extension of the hood, a swing-member pivoted to the base-bracket in a manner permitting a swing-like movement to and from the flap, a pull-member slidably mounted on the swing-member and spring-actuated in the direction towards the base bracket, the said flap-bracket having a pair of arms extending one on each side of the pull-member and the said pull-member having a pair of arms projecting crosswise from the pull-member and adapted to exert pressure on the arms of the flap-bracket to fasten the flap, the said arms of the pull-member located on the side of the pull-member which is farthest from the flap.

Signed at New York city, N. Y., on Sept. 2, 1927.

JOSEPH G. C. MANTLE.
